UNITED STATES PATENT OFFICE.

ABRAM B. TILTON, OF BAYHEAD, NEW JERSEY.

REVOLVING TOY.

1,223,643.

Specification of Letters Patent. Patented Apr. 24, 1917.

Application filed May 10, 1916. Serial No. 96,671.

To all whom it may concern:

Be it known that I, ABRAM B. TILTON, a citizen of the United States, residing at Bayhead, in the county of Ocean and State 5 of New Jersey, have invented new and useful Improvements in Revolving Toys, of which the following is a specification.

This invention relates to a toy and more particularly to a wind propelled device, and 10 it has for its object to provide amusement devices automatically propelled by air current.

A very important feature of my invention is the novel manner of associating the 15 elements so that the same may substantially withstand great wind pressure.

With these and other objects in view the invention will be better understood from the following detailed description taken in connection with the accompanying drawings, 20 wherein—

Figure 1 is a side elevation of the device. Fig. 2 is a top plan view thereof.

Fig. 3 is a sectional view on the line 3—3 25 of Fig. 2.

Fig. 4 is a longitudinal sectional view through the boat.

Fig. 5 is a cross sectional view of the boat showing the coöperation between the flange 30 of the track and the projection.

Referring to the drawings, the numeral 1 designates a handle, to the intermediate portion of which is connected certain ends of L shape brace rods 2, the remaining ends of 35 which are secured to a circular track 3, formed with an upstanding annular flange 4.

An arm 5 has one end swingingly connected to the upper end of the handle by means of a pin 6, while the remaining end of the 40 arm houses a rotatable element 7 that bears directly upon the track. Secured to the arm is the forward end of a boat 8 shown in this particular instance as having a sail 9 by means of which the arm and boat may be rotated around the handle upon the passage 45 of an air current. The keel of the boat is formed with a projection 10 resting upon the body of the track and arranged in abutting relation with the flange 4 so that the 50 excessive strain to which the parts are subjected by strong air currents may be properly distributed. Depending from the arm

5 is a rod 11 supporting a figure 12 in the form of a fish. Upstanding from the arm is a rod 13 supporting at its upper end above 55 the sail of the boat a figure 14 in the form of a bird.

In the operation of the device, the air pressure against the sail causes the arm to rotate about its pivot with the fish traveling 60 in a circle below the boat, and the bird in a circle above the boat.

It is of course to be understood that any number of boats may be provided so that air currents in one particular direction will 65 continuously rotate the apparatus.

From the foregoing description taken in connection with the accompanying drawings it should be apparent that I provide a device which is admirably adapted for the 70 purpose for which it is intended, that the device is simple, durable of construction and automatically operated, and further may be manufactured and sold at a comparatively low cost.

What I claim is:

1. A toy comprising a handle, a track supported by the handle, an arm having one end rotatably connected to said handle and its other end slidably mounted on the 80 track, a ball bearing arranged to reduce friction between the mentioned end of the arm and the track, and an amusement device supported by the arm.

2. A toy comprising a handle, a flanged 85 track supported by the handle, an arm having one end rotatably connected to said handle and its other end slidably mounted on said track, and a sail boat having its forward end secured to said arm and formed 90 with a projection slidable on the track and in abutting relation with the flange of the track.

3. A toy comprising a handle, a flange track supported by the handle, an arm having one end rotatably connected to said handle, a ball bearing rotatably mounted in the other end of the arm and running on said track, a sail boat secured to the arm, and an auxiliary amusing device supported from 100 said arm above and below said sail boat.

In testimony whereof I affix my signature.

ABRAM B. TILTON.

Copies of this patent may be obtained for five cents each, by addressing the "Commissioner of Patents, Washington, D. C."
